US0D1088015S

(12) **United States Design Patent** (10) **Patent No.:** **US D1,088,015 S**
(45) **Date of Patent:** **** Aug. 12, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Aurelio Guzmán**, San Jose, CA (US);
Christopher Daryl Soli, Mountain
View, CA (US)

(73) Assignee: **Apple Inc.**, Cupertino, CA (US)

(**) Term: **15 Years**

(21) Appl. No.: **29/956,188**

(22) Filed: **Aug. 6, 2024**

Related U.S. Application Data

(63) Continuation of application No. 29/890,000, filed on
Apr. 19, 2023, now Pat. No. Des. 1,041,492, which is
a continuation of application No. 29/838,581, filed on
May 13, 2022, now Pat. No. Des. 988,364, which is
a continuation of application No. 29/738,897, filed on
Jun. 20, 2020, now Pat. No. Des. 951,997.

CLAIM

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design. The broken lines within the peripheral dashed broken lines illustrate portions of the graphical user interface which form no part of the claimed design. Shaded and faded portions shown within broken line circles form no part of the claimed design.

1 Claim, 1 Drawing Sheet
